UNITED STATES PATENT OFFICE.

LYMAN W. MERRIAM, OF FITCHBURG, MASSACHUSETTS, ASSIGNOR OF ONE-HALF TO GEORGE O. ALLEN, OF SAME PLACE.

NON-REFILLABLE BOTTLE.

SPECIFICATION forming part of Letters Patent No. 599,185, dated February 15, 1898.

Application filed June 4, 1897. Serial No. 639,453. (No model.)

To all whom it may concern:

Be it known that I, LYMAN W. MERRIAM, a citizen of the United States, residing at Fitchburg, in the county of Worcester and State of Massachusetts, have invented certain new and useful Improvements in Non-Refillable Bottles; and I do hereby declare the following to be a full, clear, and exact description of the invention, such as will enable others skilled in the art to which it appertains to make and use the same.

This invention relates to improvements in bottles or liquid-containing receptacles of the general class denominated "antirefillable" bottles, the object of the invention being to prevent the refilling of the bottle with spurious contents of fraudulent dealers after the original genuine contents of the bottle have been disposed of; and the invention therefore consists, essentially, in the construction, arrangement, and combination of parts, substantially as will be hereinafter described and claimed.

In the accompanying drawings, illustrating my invention, Figure 1 is a vertical sectional view of my improved antirefillable bottle, the mouth end only of the same being shown. Fig. 2 is a detail side elevation of the locking-stopper. Fig. 3 is a detail plan view of the bent ring employed in connection with the aforesaid stopper for locking it in the mouth end of the bottle. Fig. 4 is a side elevation of a channeled block which forms one element of my antirefillable combination. Fig. 5 is a top plan view of the channeled block shown in Fig. 4. Fig. 6 is a perspective view of the weight or device situated between the valve and the channeled block and resting on the former. Fig. 7 is a sectional view of a modification of the valve. Fig. 8 is a side elevation of the modification of the valve.

Similar letters of reference represent corresponding parts throughout the different figures.

A designates an example of bottle presented herein simply by way of illustration, the same having the interior neck-bore a , which may be of any suitable dimensions, it being at one point of a suitable diameter to provide a seat for the valve F. The diameter of the mouth between the seat of the valve F and the per-

ipheries of the mouth is suitably shaped and varied to admit the locking-stopper, the channeled block, and the weight, which coöperate as I shall presently explain. At the periphery of the mouth is inserted the locking-stopper B, having a flange B², which fits over the periphery, and having also a circumferential groove B¹, that receives the waved or bent wire ring C, which engages the rabbet A' on the inner periphery of the mouth of the bottle, as shown in Fig. 1, and in this way the stopper B is securely locked non-removably in the mouth of the bottle. This stopper B is provided with a central opening b, designed to receive a cork or other stopper. The innermost diameter of the opening b is preferably one-half inch in diameter or about one-fifth of a square inch in circular area.

The seat for the valve F is preferably five-eighths of an inch in diameter at the point of smallest diameter or about three-tenths of a square inch in circular area.

The valve F may be made of cork, glass, metal, or any other suitable material, and its shape may vary considerably. One form is represented in Fig. 1. Another form is delineated in Figs. 7 and 8. It may, if preferred, be made of a combination of glass and cork or other materials. When it is of the form shown in Fig. 7, it is preferably provided with an inset packing-ring of cork, as shown at f. It preferably has depending guides of the form F' shown in Fig. 1 or the form F² shown in Figs. 7 and 8. The valve F preferably has a weight of about fifty grains, although it can be made to successfully operate if its weight varies from forty grains to sixty grains, and I therefore fix these limits for the proper weight of the valve for the given dimensions of bottle-neck.

The channeled block D is situated below the locking-stopper B, within the mouth of the bottle A, and resting in a stationary position on the ledge A², formed within the mouth A, the said channeled block resting between the shoulder A³ and the stopper B, the latter having on its under side a conical seat or recess to receive the upper similarly-shaped part of the block D. The periphery of the block D is provided with several notches or openings cut in the edge of block D, as is most clearly

shown in Fig. 5, said notches being represented by the reference-letter D'; also, the upper part of block D is provided with several vertical notches or grooves cut therein 5 at D². It will be evident upon inspection of Figs. 4 and 5 that the peripheral openings D' are not in line with the vertical openings D² and that the passage of a wire or other instrument downwardly through the vertical openings D² would not be effective in reaching the peripheral openings D' for the purpose of passing therethrough and tampering with the valve beneath. These vertical openings D² are situated beneath the stopper-opening b.

15 It will be evident that in pouring liquid out of the bottle it will first pass through the peripheral openings D', then around the periphery of the block D until it reaches the several vertical openings D², through which it will 20 pass, reaching the stopper-opening b and emerging thence from the bottle. The sum total of the several vertical openings D², which openings I term the "outlet-openings" of the channeled block, constitutes an area of about 25 one-seventh of a square inch; but this area may vary from one-twelfth of a square inch to one-fifth of a square inch. In practice I have found that one-twelfth of a square inch is as small as is practicable for the area of the 30 outlet-opening and that good results may be achieved if the opening be no smaller than one-twelfth of a square inch and no larger than one-fifth of a square inch—i. e., for the given diameter of the bore of the bottle-neck.

35 The sum total of the several peripheral openings D' may vary considerably without any material or marked effect upon the operation of the combination. I commonly employ in practice four of the vertical outlet-openings D² and likewise four of the peripheral openings D'; but the required area of outlet-openings, which, as I have said, is in the present example one-seventh of a square inch, (with a permissible variation of from 40 one-twelfth to one-fifth,) may be subdivided into less than four outlets or more than four, as preferred. On the under side of the channeled block D is a central cone D³, surrounded by a V-shaped groove D⁴, which groove is cut 45 in the under side of the block D, so as to leave said conical projection D³.

50 E denotes a weight situated between the valve and the channeled block, said weight being movable and having a hollow conical extension e on its upper side which is designed to fit loosely into the groove D⁴ and embrace the cone D³ and which likewise enables the weight E when below the block D to maintain the proper relative position to the other parts, said weight resting upon the valve, as shown in Fig. 1. The weight of this weight E is preferably one hundred and thirty-two grains, although it may be as light as one hundred and thirty grains; but it should not be less than the latter weight, although it may be considerably heavier than one hundred and thirty-two grains, if desired. On the upper

edge of weight E are several small projections or lifts e' e', which come in contact with the lower face of the block D when the conical extension e engages the cone D³, said lifts being for the purpose of preventing a too close contact between the weight and the block D. Thus it will be seen that for a given area of valve-seat or outlet-opening in the bottle-neck, which area I have designated as three-tenths of a square inch, and for a given area of nozzle-opening at the mouth end of the bottle-neck, the area of which opening I have specified as one-fifth of a square inch, the 75 area of the outlet-ports in the channeled block should be about one-seventh of a square inch, with a permissible variation of from one-twelfth to one-fifth. The weight of the valve should be about fifty grains and the weight 80 of the weight proper about one hundred and thirty grains, or more. Practical tests have demonstrated the correctness of these several dimensions and weights, and it has been found that any material departure therefrom is attended with bad results, while with these 85 specified proportions excellent results have been attained, and it has been found impossible to refill a bottle of the kind referred to after once its contents have been emptied. 90 The specified proportions not only permit facility in emptying the original contents from the bottle, but they effectually preclude the readmission of anything more than a slight amount of liquid into the interior of 95 the bottle again.

The conical extension e of the weight E should be so proportioned as to have sufficient movement when it drops into groove D⁴ to allow the valve F to move from its seat the distance of about one-eighth of an inch. I find that this gives the best results.

The operation of my improved combination will be evident from the foregoing description without the necessity of additional detail. 105 In emptying the bottle of its contents it will be perceived that when it is reversed in position the weight E will drop into groove D⁴, thus allowing the valve to be removed from its seat and the bottle's contents to pass through 110 the valve and then through the other parts, finding exit at the outlet-opening b.

115 Within the bottle-mouth A and around the lower periphery of the locking-stopper B is a packing-ring H, of cork or some similar suitable material, which is situated tightly between a shoulder on the inner face of the bottle-mouth A and the lower portion of the locking-stopper B for the purpose of making a tight joint at that point and preventing any 120 possibility of leakage of the contents of the bottle around the locking-stopper at the point where the latter comes in contact with the periphery of the mouth of the bottle.

125 Having now fully described my invention, what I claim as new, and desire to secure by Letters Patent, is—

1. In a non-refillable bottle, the combination with the bottle-neck having a bore of a

given diameter, the locking-stopper inserted in the mouth end of the bottle-neck and provided with an opening of a given size, the circular area of said opening in the locking-stopper being to the valve-seat in the bore of the neck substantially as two to three, a channeled block situated within the bottle-mouth below the locking-stopper and having an outlet whose area is substantially equal to that of the outlet in the locking-stopper but variable within certain narrow limits, a valve operative in connection with the valve-seat, and a movable weight between the valve and the channeled block, said weight being from two to three times as heavy as the valve, substantially as described.

2. In a non-refillable bottle, the combination with the bottle-neck having in the bore thereof a valve-seat, a locking-stopper inserted non-removably in the mouth end of

the bottle and provided with a central outlet-opening having a ratio to the valve-seat as two to three or thereabout, a channeled block in the bottle-mouth below the bottle-stopper and having an outlet which is subdivided into several openings, the sum total of which presents an area substantially equal to that of the opening in the locking-stopper but adapted to be varied if desired within certain narrow limits, a valve on the valve-seat, and a weight between the valve and the channeled block, said weight being from two to three times as heavy as the valve, substantially as described. 25
